UNITED STATES PATENT OFFICE.

FRANZ X. WAGNER, OF NEW YORK, N. Y., ASSIGNOR TO UNDERWOOD TYPEWRITER COMPANY, OF NEW YORK, N. Y., A CORPORATION OF NEW JERSEY.

TYPE-WRITING MACHINE.

No. 848,707.

Specification of Letters Patent.

Patented April 2, 1907.

Application filed March 27, 1905. Serial No. 252,382.

To all whom it may concern:

Be it known that I, FRANZ X. WAGNER, a citizen of the United States, residing in Bronx borough, New York city, in the county of New York and State of New York, have invented certain new and useful Improvements in Type-Writing Machines, of which the following is a specification.

This invention relates to the ribbon-controlling devices of type-writing machines, and particularly to the mechanism in front-strike and other visible-writing machines by which the ribbon is caused to cover and uncover the printing-point at each type-stroke.

The object of my invention is to produce a simple and satisfactory mechanism for enabling the operator to bring into use either the upper or the lower color-band of a polychromatic ribbon and also to render the ribbon-vibrating mechanism ineffective during the operation of the types at will, so as to adapt the machine for writing stencils for use in mimeographic work.

A further object of the invention is to provide means for enabling the operator positively and certainly to bring into use either color-band desired without the usual necessity of first striking a type-key to ascertain what color is written thereby and without the liability of making an error as to the color and also to determine at any time by a glance which color-band of the ribbon is in use or whether the ribbon-vibrating mechanism is thrown out of use.

In carrying out my invention I provide between the ribbon-carrier of the well-known "Underwood" type-writing machine and the lever which vibrates said carrier at the key-strokes a member having steps, and I provide means for enabling said lever to engage either of said steps, and hence to move said ribbon up and down over the printing-point, thus bringing into use either the top color-band or the lower color-band of the ribbon, according to the particular step which is in use. Said stepped member is preferably upon the ribbon-carrier itself. I provide upon the framework of the machine a shifter-bar which can control said stepped member, while not interfering with the up and down movements of the ribbon-carrier. The shifter-bar I operate by means of two keys, one of which I color red and the other of which I color black. The connection between the

keys and the ribbon-carrier are such that when the red key is depressed the red band of the ribbon is put into use; on the contrary, when the black key is depressed the black band is put into use. Other colors of ribbon and keys, however, may be employed. Other objects and advantages will hereafter appear.

In the accompanying drawings, Figure 1 is a sectional side elevation taken through the ribbon mechanism of an Underwood type-writing machine, and showing my improvements applied thereto. The parts are in normal position, but the platen and ribbon mechanism are shown elevated to the position for enabling the capital types to print. Fig. 2 is a sectional rear view of the parts see 1 at Fig. 1. Fig. 3 is a plan of the same. Fig. 4 is a perspective view of the principal portions of the ribbon-vibrating mechanism, the parts being shown in the positions seen at Fig. 1. Fig. 5 is a rear view of the ribbon-carrier, but showing the parts shifted to such a position as to cause the lower color-band of the ribbon to be brought into use, but otherwise in the same position as at Fig. 2. Fig. 6 shows the parts in printing position, but at the lower-case shift. Fig. 7 is a view similar to Fig. 5, but showing the parts shifted to position for causing the lower color-band of the ribbon to be brought into use.

As usual in the Underwood front-strike writing-machine, type-bars 1, carrying lower-case types 2 and upper-case types 3, strike rearwardly through a ribbon 4, against a platen 5. Said platen is usually mounted in a frame or carriage (not shown) which runs upon a rail 6, and this rail is shiftable up and down, together with the platen-frame and platen, to enable the types 2 and 3 to print. At Fig. 6 the parts are in lower-case position to enable the types 2 to print, while at all the remaining figures the parts are in upper-case position to enable the types 3 to print. At each type impression the ribbon is first vibrated up to cover the printing-point and then down to disclose the writing, these movements being effected by a carrier 7, standing vertically in front of the platen and guided in a casting or segment 8, in which are also mounted the type-bars 1. This ribbon-carrier is actuated by a lever comprising arms 9 and 10. The lever is pivoted at

11 upon a bracket 12, which is fastened to the platen-shifting rail 6. The arm 9 extends forwardly and the arm 10 upwardly from said pivot. The necessary vibrations 5 of the latter are effected by a plate or lug 13, having a vertical slot 14 to engage a wrist 15 upon said lever-arm 10. Said slotted member 13 is fixed upon a table or frame 16, which reciprocates at the strokes of the type-bars 10 1 in a well-known manner, said table or frame 16 having a curved universal bar 17, which is engaged by heels 18, formed upon the type-bars. Each type-bar as it swings to the platen pushes back said universal bar-frame, together with the slotted member 13, thereby vibrating the lever-arm 10 backwardly and elevating the lever-arm 9, so as to raise the ribbon-carrier 7, together with the ribbon. The return movements of 15 20 said universal-bar frame are effected by a spring 19.

The ribbon is formed along its upper portion with a band 20, which is charged with black ink, and along its lower portion with a band 21, which is charged with red ink, although other contrasting colors are sometimes used. To enable either color to be used at will, I provide means for enabling the lever-arm 9 to raise the ribbon-carrier to different elevations, giving the same a short stroke when it is desired to use the black upper band 20 and a long stroke when it is desired to use the red lower band 21. To this end I pivot at 22 upon the rear face of the 25 30 ribbon-carrier 7 a plate 23, having at its lower ends steps 24 and 25, with either of which said lever may coöperate, whereby strokes of different lengths are given to the ribbon-carrier, owing to the difference in the 35 40 distance of the steps from the lever-arm 9. When it is desired to use the black band 20, the upper step 24 is brought into play by vibrating the stepped member 23 to the right at Fig. 7, so that the initial portion of the upward stroke of the lever-arm 9 is idle, and the ribbon-carrier is lifted only during the 45 50 last portion of the lever-stroke just sufficient to cause the black band 20 to cover the printing-point. When, however, it is desired to use the red lower band 21, the stepped member 23 is vibrated to the left at Figs. 5 and 6, so that the lower step 25 stands opposite the lever-arm 9, and there is little or no lost motion of the latter during its up stroke, 55 60 whereby the ribbon-carrier is given a full upward movement until the lower red band 21 stands over the printing-point. While said steps are shown in the form of projections, still the projections may be omitted within the scope of the invention. It is not necessary in all cases that the shiftable stepped member 23 be pivoted upon the ribbon-carrier or pivoted at all or even positively attached to a moving member.

65 Between the steps 24 and 25 is an opening

26 of sufficient width to permit the lever-arm 9 to play freely up and down therein. When said shiftable plate 23 stands in vertical or midway position, as at Figs. 2 and 4, the lever plays idly up and down in said 70 opening during the type-strokes and the ribbon is not moved at all from its normal position. Thus the types strike off the ribbon, this provision being useful for mimeograph and other kinds of work.

75 For shifting the stepped member 23 to either one of its three required positions I provide upon a fixed part 8 of the framework of the machine a shifter-bar 27, having forks or slot member 28 extending down in rear of said plate 23, said forks straddling a pin 29, which projects from said plate 23. The forks (or the intervening slot) stand vertically so as not to interfere at any time with the up and down movements of the pin 29 or the 80 ribbon-carrier. By sliding the shifter-bar 27 to the left or right the forks are caused to engage the pin 29 and vibrate the carrier to either of the three positions illustrated in the several figures. It will be seen that the 85 shifter-bar extends to the side of the machine, and, if desired, it may be prolonged to form a finger-piece 30, projecting at the right-hand side of the machine, convenient for the operator. Upon the bar I form three notches 31, 90 95 either of which is engageable by a spring-detent 32 for detaining the shifter-bar, and hence the stepped plate 23, in either of the three positions referred to. I prefer, however, to provide a rock-shaft 33 having an 100 upstanding arm 34 to engage a notch 35 formed in the end of the shifter-bar 27, so that by rocking said shaft the bar may be shifted. Upon the forward end of said shaft and just in front of a vertical plate 36, which 105 stands in rear of the usual type-keys 37, I provide a two-arm lever 38, one arm carrying a red key 39 and the other carrying a black key 40. It will be seen that when the black key 40 is depressed the arm 34 is rocked to the 110 right at Fig. 2, and consequently the stepped member 23 is swung to the Fig. 7 position, which is the position for bringing the black band of the ribbon into use. When the red key is depressed, the member 23 is swung to 115 the Fig. 5 position for bringing the red band into use. When the keys are level or in midway positions, as seen at Figs. 2 and 4, the plate 23 stands in a position where the opening 26 is opposite the lever, and hence the 120 ribbon does not move up at the type-strokes. The provision of the red and black keys is a great convenience, since the operator is enabled to tell by merely glancing at them which color-band of the ribbon is in use, and at 125 any time a simple touch upon a key changes the color. There is no possibility of printing the wrong color upon the paper, which has heretofore been a source of great annoyance to the operator.

The weight of the ribbon-carrier assists the return thereof to normal position; but I prefer to provide upon the bottom of the ribbon-carrier a cross-pin 41 beneath the end of the lever, so that the latter in its return movement may insure the return of the ribbon-carrier. When the shift-rail and platen are elevated to enable the upper-case types to print, the lever is carried bodily up by reason of its being pivoted upon the bracket 12, that is fixed to the shift-rail 6, and at the same time the ribbon-carrier is elevated by means of an arm 42, formed upon said bracket 12 and projecting forwardly therefrom beneath the foot of the ribbon-carrier.

Overthrow of the ribbon-carrier when in upper-case position is prevented by the lower end of one of the forks 28, which is in the path of the projecting step 24 and serves as a stop therefor. The overthrow of the ribbon-carrier when the parts are in lower-case position is prevented by a stop 43 in the path of the projecting step 25, as at Fig. 6. This stop 43 is pivoted at 44 upon the rear side of the segment or framework 8 and at its lower end has a cam 45, with which engages the side edge of bracket-arm 12, as seen at Figs. 2 and 6, so that when said bracket-arm is being elevated it cams the stop 43 out of operative position, as at Fig. 2, so that it cannot interfere with the desired upward movements of the ribbon-carrier. A compression-spring 46 is provided to insure the proper vibration of the stop 43 when the parts are shifted back to lower-case position.

Variations may be resorted to within the scope of my invention, and portions of my improvements may be used without others.

Having thus described my invention, I claim—

1. In a type-writing machine, the combination with types and a platen, of a ribbon-carrier, a part which is reciprocated at the operations of the types, and a member shiftable to different positions upon said ribbon-carrier, and having a plurality of steps movable into the path of said reciprocating part so as to effect variable movements of said ribbon-carrier and bring different color-bands 50 on the ribbon into use.

2. In a type-writing machine, the combination with types and a platen, of a ribbon-carrier, a member shiftable thereon and having step portions, a lever which may engage with either of said step portions according to the adjustment of said shiftable member, and means for reciprocating said lever at the type-strokes.

3. In a type-writing machine, the combination with types and a platen, of a ribbon-carrier, a stepped member movable thereon, means including a finger-piece for adjusting said stepped member transversely of the ribbon-carrier, and a lever movable at each key-

stroke and engageable with either step upon 65 said step member.

4. In a type-writing machine, the combination with types and a platen, of a ribbon-vibrator, a stepped member pivoted thereon, a shifter mounted upon the framework and 70 capable of vibrating said pivoted member to bring either step thereon into use, and a lever reciprocated at each type-stroke and engageable with said stepped member.

5. In a type-writing machine, the combination with types and a platen, of a ribbon-vibrator, a stepped member movable transversely thereon, a stationary shifter having a pin-and-slot engagement with said stepped member so as to effect transverse adjustment 80 of the latter but permit ribbon-vibrating movement thereof, and a lever reciprocated at the key-strokes and engageable with either step of said stepped member.

6. In a type-writing machine, the combination with types and a platen, of a ribbon-carrier, a transversely-movable stepped member thereon, a lever reciprocated at the type-strokes and engageable with either step of said stepped member, means for detaining 90 said stepped member in different positions to cause said lever to engage either step thereon, and means for enabling said lever to return said carrier to normal position.

7. In a type-writing machine, the combination with types and a platen, of a ribbon-carrier, an arm pivoted thereon and having steps, a member reciprocated at the type-strokes and having a part to engage either step, a shifter mounted upon the framework 95 and having a slot extending in the direction of the movement of said ribbon-carrier, and a pin upon said stepped member engaging said slot.

8. In a type-writing machine, the combination with types and a platen, of a part reciprocated at the key-strokes, a ribbon-carrier, a member pivoted upon said ribbon-carrier and having steps, and a finger-piece for effecting movement of said pivoted member 110 to shift either step into the path of said reciprocating part.

9. In a type-writing machine, the combination with types and a platen, of a part reciprocated at the key-strokes, a ribbon-carrier, a member mounted upon said ribbon-carrier and having steps, a finger-piece for effecting movements of said stepped member to shift either step into the path of said reciprocating part, and means for detaining said 120 stepped member in the different positions to which it is shifted.

10. In a type-writing machine, the combination with types and a platen, of a part reciprocated at the key-strokes, a ribbon-carrier, a member mounted upon said ribbon-carrier and having steps, a shifter mounted upon the framework of the machine and con-

- neeted to said stepped member, for effecting movements of the latter, to bring either step into the path of said reciprocating member, means for detaining said shifter in different 5 positions, and a finger-piece controlling said shifter.
11. In a type-writing machine, the combination with types and a platen, a part reciprocated at each type-stroke, a ribbon-carrier, a stepped member between said ribbon-carrier, and said reciprocating part, and means for adjusting said stepped member to effect different vibrations of the ribbon-carrier to bring either color-band of the ribbon into use. 10
12. In a type-writing machine, the combination with types and a platen, a part reciprocated at each type-stroke, a ribbon-carrier, a stepped member between said ribbon-carrier and said reciprocating part, means for 20 adjusting said stepped member to effect different vibrations of the ribbon-carrier to bring either color band of the ribbon into use, a shifter upon the framework controlling the position of said stepped member, and means 25 for detaining said shifter in a plurality of positions.
13. In a type-writing machine, the combination with types and a platen, of a ribbon-carrier, means vibrating the ribbon-carrier at the type-strokes, a plurality of differently-colored keys, and means enabling each key to control the vibration of the ribbon-carrier so as to bring into use the ribbon-band having the color corresponding to the operated key. 30
14. In a type-writing machine, the combination with types and a platen, of a ribbon-carrier, an actuator reciprocated at the type-strokes, a plurality of differently-colored keys, and means between said actuator and said ribbon-carrier and controlled by said colored keys for bringing differently-colored bands of the ribbon into use. 40
15. In a type-writing machine, the combination with types and a platen, of a ribbon-vibrator, an actuator reciprocated at the type-strokes, a two-arm lever, a key upon each arm of the lever, and means between said actuator and said vibrator and controlled by said lever, for causing such movements of said carrier as to bring different color-bands of the ribbon into use. 45
16. In a type-writing machine, the combination with types and a platen, of a ribbon-carrier, a part which is reciprocated at the operations of the types, a member having steps and pivoted to one of said ribbon-carrier and reciprocating parts, and means for effecting such relative movements of said 55 stepped member, as to cause the reciprocating part either to effect variable movements of said ribbon-carrier to bring different color-bands on the ribbon into use, or to fail to move the carrier, at the will of the operator. 60
17. In a type-writing machine, the combination with types and a platen, of a ribbon-carrier, a part which is reciprocated at the operations of the types, a member having steps and shiftable on one of said elements, and a finger-piece upon the framework connected to said stepped member and capable of shifting the same, so that the ribbon-carrier is either rendered ineffective at the type-strokes or caused to bring different widthwise portions of the ribbon into use. 70
18. In a type-writing machine, the combination with types and a platen, of a ribbon-carrier, a member having steps and shiftable thereon; a finger-piece upon the framework and connected to said stepped member, a part which is reciprocated at the operations of the types, said stepped member being movable into such positions as to cause said reciprocating part either to move the carrier different distances or not at all, and means 75 for detaining said stepped member in its different positions.
19. In a type-writing machine, the combination with types and a platen, of a member having steps, a ribbon-carrier, a part reciprocating at the type-strokes, said stepped member being shiftable upon one of said elements so as to cause said ribbon-carrier to be moved different distances, by the engagement of 80 said reciprocating part with said steps, and means for rendering said reciprocating member ineffective at will. 90
20. In a type-writing machine, the combination with types and a platen, of a ribbon-vibrator, a member having steps and shiftable thereon, a shifter mounted upon the framework, and a part reciprocated at each type-stroke and engageable with said stepped member, said shifter capable of moving said 95 stepped member either so that different steps thereof may engage said reciprocating part, or so that said carrier is inoperable by said reciprocating part, at will. 100
21. In a type-writing machine, the combination with types and a platen, of a ribbon-carrier, a part which reciprocates at the type-strokes, and a shiftable member having steps either of which is engageable by said reciprocating part, said steps separated by an opening in which said reciprocating part may 110 work idly, and means for detaining said stepped member in such positions that said reciprocating part may engage either of said steps or work idly in said opening, at the will of the operator. 115
22. In a type-writing machine, the combination with types and a platen, of a ribbon-carrier, a part reciprocated at the type-strokes, a member shiftable upon one of said carrier and reciprocating elements; said stepped member being formed with an opening between said steps; a shifter mounted upon the framework and connected to said stepped member; and means for detaining said shifter in any one of three positions, so as to cause 120 125 130

either of said steps or said opening to stand opposite to said reciprocating part.

23. In a type-writing machine, the combination with types and a platen, of a ribbon-carrier, a part reciprocated at the type-strokes, a member provided with steps and an intervening opening and pivoted upon said carrier, a rocking device upon the framework provided with keys, means connecting said rocking device to said stepped member, and means for detaining said stepped member with either one of said steps or said opening opposite to said reciprocating part.

24. In a type-writing machine, the combination with types and a platen, of a ribbon-carrier, a part reciprocated at the type-strokes, a member having two steps and an intervening opening and shiftable transversely upon said carrier, a shifter-bar mounted upon the framework and controlling said stepped member, means for detaining said shifter-bar in any of three positions, and a rock-shaft connected to said shifter-bar and having a pair of keys.

25. 25. In a type-writing machine, the combination with types and a platen, of a ribbon-carrier, an actuator reciprocated at the type-strokes, a shiftable member between said actuator and said carrier to enable similar movements of said actuator to effect variable movements of the carrier, and a plurality of differently-colored keys operatively connected to said shiftable member.

26. In a type-writing machine, the combination with types and a platen, of a ribbon-carrier; means for vibrating the ribbon-carrier at the type-strokes; said vibrating means including a part shiftable to different positions for causing different color-bands on the ribbon to be brought into use; differently-colored keys mounted upon the framework; and means enabling said keys to shift said shiftable member to different positions.

27. In a type-writing machine, the combination with keys and a platen, of a ribbon-carrier, a part reciprocated at the type-strokes, a stepped member between said ribbon-carrier and said reciprocating part, a shifter controlling said stepped member so as to bring either step thereof into co-operation with said reciprocating part, and keys mounted upon the framework and having means for moving said shifter to different positions.

28. In a type-writing machine, the combination with keys and a platen, of a ribbon-carrier, a part reciprocated at the type-strokes, a stepped member between said ribbon-carrier and said reciprocating part, a shifter controlling said stepped member so as to bring either step thereof into co-operation with said reciprocating part, and keys having means for moving said shifter to different positions, said keys being differently colored.

29. In a type-writing machine, the combi-

nation with types and a platen, of a ribbon-vibrator, a part reciprocated at the type-strokes, a stepped member shiftable upon said ribbon-vibrator to bring either step thereon into co-operation with said reciprocating member, a shifter mounted upon the framework and connected to said stepped member, a two-arm lever operatively connected to said shifter, keys mounted upon the arms of said lever, and means for detaining said shifter in different positions.

30. In a type-writing machine, the combination with types and a platen, of a ribbon-vibrator, a part reciprocated at the type-strokes, a stepped member pivoted upon said carrier and pivoted so as to bring either step thereof into co-operation with said reciprocating part, a pin upon said pivoted member, a shifter-bar mounted upon the framework and having a slot to engage said pin, said slot extending in the direction of movement of said ribbon-carrier, a detent for holding said shifter-bar in a plurality of positions, a rock-shaft connected to said shifter-bar, arms projecting from said rock-shaft upon opposite sides thereof, and keys upon said arms.

31. In a type-writing machine, the combination with types and a platen, of a ribbon-carrier, means for vibrating the ribbon-carrier at the type-strokes, a plurality of differently-colored keys mounted upon the framework of the machine, and means for enabling said keys either to control the vibration of the ribbon-carrier so as to bring into use different widthwise portions thereof, or to cause said ribbon-carrier to be inoperative during the type-strokes.

32. In a type-writing machine, the combination with types and a platen, of a ribbon-carrier, an actuator reciprocated at the type-strokes, a plurality of differently-colored keys, and means between said actuator and said ribbon-carrier and controlled by said keys for bringing different widthwise portions of the ribbon into use; said means being movable by said keys to an inoperative position.

33. In a type-writing machine, the combination with types and a platen, of a ribbon-vibrator, an actuator reciprocated at the type-strokes, a two-arm lever, a key upon each arm of the lever, and means controlled by said lever for either bringing different widthwise portions of the ribbon into use, or causing said ribbon to be ineffective at the type-strokes, at will.

34. In a type-writing machine, the combination with types and a platen, shiftable to enable different types to print, of a ribbon-vibrating mechanism including a ribbon-carrier which is shiftable with the platen, a device shiftable transversely upon said ribbon-carrier for enabling different widthwise portions of the ribbon to be brought into use, and a shifter mounted upon the framework

of the machine and connected to said transversely-shiftable device and provided with a finger-piece.

35. In a type-writing machine the combination with types and a platen shiftable to enable different types to print, of a rail or frame shifting with the platen, a lever shifting with said rail, a ribbon-carrier having steps for engagement by said lever and also shifting with the platen, and means for causing said lever to engage either step at will.

36. In a type-writing machine, the combination with types and a platen shiftable to enable different types to print, of a frame shifting with the platen, a lever reciprocated at the type-strokes and shifting with said frame, a ribbon-carrier, means upon said frame for shifting said ribbon-carrier with the platen, a member upon said ribbon-carrier shiftable transversely and having steps either of which may be engaged by said lever, and means upon the framework of the machine for shifting said stepped member.

37. In a type-writing machine, the combination with types and a platen shiftable to enable different types to print, of a frame shifting with the platen, a lever reciprocated at the type-strokes, and shifting with said frame, a ribbon-carrier having steps engageable by said lever, means for shifting said

ribbon-carrier with the platen, and means upon the framework of the machine for effecting a relative shifting movement between said lever and said steps, an opening provided between said steps in which said lever may work idly, and said shifting means including a pair of keys whereby either of said steps or said opening may be brought opposite to said lever.

38. In a type-writing machine, the combination with types and a platen shiftable to enable different types to print, of a frame shifting with the platen, a lever reciprocated at the type-strokes, and shifting with said frame, a ribbon-carrier, means upon said frame for shifting said ribbon-carrier with the platen, a member upon said ribbon-carrier shiftable transversely, and having steps either of which may be engaged by said lever, means for shifting said stepped member, a stop for limiting the printing stroke of said ribbon-carrier when the platen is in lower-case position, and means upon said platen-shifting frame for moving said stop out of working position when the platen shifts.

FRANZ X. WAGNER.
